STEERING MECHANISM

Fred Gasche, Titusville, Pa., assignor to Struthers
Wells Corporation, Titusville, Pa., a corporation
of Maryland

Application October 7, 1943, Serial No. 505,337

1 Claim. (Cl. 60—52)

This invention relates to a control mechanism for the hydraulic steering mechanism of ships, and has for its object the provision of a mechanism of this character which is simpler and less expensive in construction than those heretofore in use, which is positive in its operation, and which will reliably hold the rudder in any desired position with a minimum expenditure of power.

In the accompanying drawings:

Fig. 1 is a diagrammatic plan view of the control mechanism embodying this invention.

Fig. 2 is an elevation of a portion thereof.

Fig. 3 is a fragmentary, vertical longitudinal section, on an enlarged scale, taken substantially on line 3—3, Fig. 1.

Figs. 4 and 5 are cross sections taken on the correspondingly numbered lines in Fig. 3 and showing the Geneva stop mechanism in one position.

Fig. 6 is a cross section taken on line 6—6, Fig. 3 but showing the Geneva stop mechanism in another position.

In the following description, similar reference characters indicate like parts in the several views.

The steering mechanism of the ship in connection with which the present invention is used may be variously constructed, but that shown in the drawings, as an example, capable of embodying this invention is constructed as follows:

The numeral 10 represents the upright rudder stock or shaft which is journaled in any suitable manner on the rudder post of the ship and provided on its lower part with the usual rudder 11, while its upper end or head has secured thereto a tiller or steering arm 12 which in this instance projects forwardly. A horizontally turning movement is imparted to this tiller by a hydraulic actuator consisting of two hydraulic power cylinders 13, 14 mounted transversely on the ship on opposite sides of the tiller and a double ram or plunger movable lengthwise with its outer ends 15, 16 in said cylinders and provided with a cross head 17 which slides radially in a guideway 18 in the tiller. Upon alternately introducing liquid under pressure into the outer ends of these cylinders and withdrawing the same therefrom the double ram or plunger will be reciprocated and cause the tiller and rudder to be rocked toward and from a central position for steering the ship.

The liquid for operating the double ram or plunger in this manner may be alternately supplied to and withdrawn from the outer ends of

the hydraulic cylinders by various means, such for example, as those which are shown in United States Patents Nos. 924,787, 1,108,443 and 1,993,475 and which include a Waterbury hydraulic pump 19 driven by a continuously running electric motor 20, conduits 21, 22 connecting opposite sides of this pump with the outer ends of the power cylinders and a reversible control mechanism 23 having a valve shifting rod or stem 24 which upon resting in its central position will cause the pump to not discharge any liquid, but which upon being moved in one direction will cause the pump to deliver oil or other liquid under pressure through one of the conduits to one of the cylinders and withdraw liquid through the other conduit from the other cylinder and thus cause the rudder to be turned in one direction from its central position, and vice versa.

The shifting rod of the reversible control mechanism is set by a control shaft 25 which may be operated either by a hand or track wheel 26 connected directly therewith or this shaft may be provided with an extension 27, as shown by dotted lines in Fig. 1, which is connected with a manually operated transmitting mechanism in the pilot house located on the ship remote from the steering mechanism.

The control shaft 25 is arranged horizontally of the ship and extends through a stationary control box housing or casing 28 which encloses most of the parts constituting the steering mechanism. The front part of the control shaft is journaled in a bearing 29 mounted on the front part of the housing and the rear end of this shaft rotates in a bearing 30 of any suitable type arranged within the rear part of the bore of a tubular follow-up or restoring shaft 31 while the intermediate part of the control shaft is journaled by an intermediate bearing 32 on the front end of the follow-up shaft, as shown in Fig. 3. The follow-up shaft turns in a bearing 33 on the rear part of the housing.

Various means may be employed for transmitting motion from the rams or plungers to the follow-up shaft, those shown in the drawings comprising a follow-up or restoring gear rack 34 arranged parallel with the rams and connected therewith so that they move in unison and a follow-up gear pinion 35 secured to the rear end of the follow-up shaft and meshing with the gear rack. On the control shaft is mounted a spider which is rotatable about the axis of this shaft and which comprises a front section 37 journaled in a bearing 38 on a tubular differential shaft 39 which is connected by a key 36 or

otherwise with the control shaft in rear of the bearing 29, and a rear section 40 which is journaled on the control shaft by means of two bearings 41 arranged between the bearing 32 and the tubular shaft 39. The two sections of the spider extend laterally from the control shaft and have their outer parts connected by bolts 42, as shown in Fig. 3.

The numeral 43 represents a front differential gear wheel secured to the rear end of the differential shaft 39 and the numeral 44 represents a rear differential gear wheel secured to the front end of the follow-up shaft 31. The two differential gear wheels 43, 44 are arranged on opposite sides of the rear section 40 of the spider and are concentric with each other and the control shaft 25, the differential shaft 39 and the follow-up shaft 31. The numeral 45 represents an intermediate floating differential gear pinion which intermeshes on its opposite sides with the opposing faces of the differential gear wheels and which is pivoted on the rear section of the spider by means which include a pivot shaft, stud or arbor 46 mounted radially on the rear section of the spider. Shifting means are provided which cause the hydraulic shifting mechanism to hold the rudder in its assigned position, or cause the rudder to be moved different distances from its previous position and then held there.

In their preferred form these shifting means are constructed as follows:

The numeral 47 represents a rock shaft arranged parallel with the control shaft and journaled in bearings 48, 49 mounted on the front part of the control box or housing. On its outer end this rock shaft is provided with a rock arm 50 which is operatively connected with the control rod or stem 24 by an elbow lever 51 pivoted on the pump casing and having one of its arms connected with the pump control stem 24 while its other arm is connected by a rod 52 with the rock arm 50.

On its inner or rear end the rock shaft 47 is provided with a lock arm 53 of a locking device which is adapted to oscillate with this rock shaft and which is provided with a radial slot 54 and two curved locking faces 55, 57 on opposite sides of the radial slot, the axis of each of these faces being concentric with the axes of the control shaft 25 when the axis of the respective locking face and those of the control shaft and rock shaft are in line, as shown in Fig. 4.

The numeral 58 represents a trip arm which is part of a trip device and which is preferably integral with the front part 37 of the spider and provided on its outer end with a trip roller or tappet 59 adapted to engage with the slot of the lock arm 53, and also provided on the periphery of its hub 60 with a receding clearance face 61 and a cylindrical locking face 62 which is concentric with the control shaft and extends from one side of the clearance face to the other.

When the trip arm is in its central position its tappet 59 is arranged in the slot of the lock arm 53, as shown in Fig. 6, in which position the lock arm is free to be turned in either direction by the tappet of the trip arm until the locking face on one side or the other of this slot engages the periphery of the locking face on the hub of the trip arm, as shown in Fig. 4, after which the rock shaft is held against further rotation but the trip arm and its hub are free to rotate further independently of the lock

arm and thus hold at rest the parts which are operatively connected with the lock arm in a manner similar to the operation of a Geneva stop mechanism.

5 The operation of this steering apparatus is as follows:

If the rudder is in its central position, as shown in Fig. 1, the pump control stem or shifting rod 24 is in its central position so that there is no discharge of liquid within the running pump at which time the trip roller or tappet 59 engages with the slot 54 in the lock arm 53, as shown in Fig. 6, and the rudder is held against movement in either direction by the liquid in the outer ends of the cylinders 13, 14 resisting the movement of the rams or plungers.

If the skipper wishes to turn the rudder so that the ship turns starboard (right), he turns the trick wheel 26 and the control shaft 25 clockwise to an extent corresponding to the degree he wishes to turn the rudder in the respective direction. During this rotation of the control shaft 25 the front differential gear wheel 43, which turns in unison therewith, causes the differential pinion 45 to roll on the rear differential gear wheel 44, which latter is standing still at this time, so that this pinion is carried bodily clockwise and causes the spider to turn in the same direction.

30 During the first part of this rotation of the spider the tappet 59 will engage the port side of the slot 54 in the lock arm 53 and turn the latter in an anti-clockwise direction and permit the tappet to move out of this slot and engage the locking face 55 of the lock arm with the cylindrical locking face 62 of the trip arm 58, as shown in Fig. 4, thereby holding the lock arm at rest but permitting the trip arm 58 to continue movement in this direction. This turning 35 movement of the rock shaft 47 in an anti-clockwise direction is transmitted by the arm 50, rod 52 and lever 51 to the pump control stem 24 so that the liquid is now forced by the pump 40 19 into the starboard cylinder 14 and liquid is withdrawn from the port cylinder 13 and thus 45 causes the rams to be moved toward the port side of the ship and turn the rudder toward the starboard side of the same causing the ship to turn starboard.

50 The extent which the rudder is thus turned toward the starboard (right) is determined by the number of degrees which the trip arm 58 is turned clockwise from its central position, inasmuch as the pump control stem will remain

55 in the respective position until the rudder has reached the desired angle. As the rams move from their central position toward the port side the restoring or follow-up rack 34 which moves in unison with the rams causes the follow-up

60 or restoring gear pinion 35 to turn anti-clockwise, whereby the rear differential gear wheel 44 will turn the intermediate pinion 45 so that it rolls on the front differential gear wheel 43 in an anti-clockwise direction and thus cause this

65 pinion to move bodily in this direction, together with the spider upon which the pinion is mounted. During this anti-clockwise movement of the spider the trip arm 58 and the hub 60 of the trip device move idly and the locking arm 53

70 remains standing still until the locking face 62 of the trip device has cleared the respective locking face 55 of the locking device and during the last part of this return or restoring movement of the trip device its tappet 59 engages the 75 slot 54 of the locking device and turns the latter

clockwise into its central position, thereby causing the pump control to be returned to its central position in which further delivery of liquid to the starboard cylinder 14 and withdrawal of liquid from the port cylinder 13 is arrested and the rudder is held in the position in which it has been set.

In the absence of further manipulation of the steering mechanism the rudder is held in a position in which it inclines toward the starboard side until such time as the course of the ship requires changing. When it is desired to again return the rudder to its central position the skipper turns the trick wheel 26 anti-clockwise whereby the front differential gear wheel 43 connected therewith will cause the intermediate gear pinion 45 to roll bodily anti-clockwise on the rear differential gear wheel 44 which is standing still at this time. During this movement of the pinion 45 the spider is also moved anti-clockwise together with the arm 58 and hub 60 of the trip device. This movement of these parts is continued until the tappet or roller 59 of the trip device has moved toward the starboard side of the slot 54 of the lock arm 53 and out of engagement therewith, thereby turning the locking arm 53 clockwise and engaging its locking face 57 with the locking face 62 of the trip device, as shown by dotted lines in Fig. 4, and thereby holding the locking device against further movement while the trip device is free to move anti-clockwise as far as required. Upon turning the rock shaft 47 clockwise in this manner the operating arm 50 thereof shifts the stem 24 of the pump control so as to cause the pump to deliver liquid into the outer end of the port cylinder 13 and withdraw liquid from the outer end of the starboard cylinder 14. When this occurs the rams are moved from port to starboard of the ship together with the follow-up gear rack 34 connected therewith, whereby the follow-up pinion 35 is turned clockwise together with the rear differential gear wheel 44 which is connected therewith by the follow-up shaft 31. Inasmuch as the floating follow-up gear pinion 45 meshes with the rear differential gear wheel 44, this pinion is rolled bodily in a clockwise direction on the front differential gear wheel 43 which is standing still at this time, thereby causing the locking device to turn anti-clockwise together with the operating arm 50 and causing the latter to shift the control mechanism of the

5 pump into central or neutral position for stopping the same and holding the rudder in its central position.

When it is desired to turn the rudder toward the port side of the ship the cycle of operations is performed in a manner reverse to those above described.

As a whole this steering mechanism is very compact and sturdy in construction, it is not liable to get out of order and can be serviced conveniently and easily, and the same permits of easily and quickly steering a ship and holding its course with a minimum expenditure of manual effort or power.

15 I claim as my invention

A steering mechanism comprising a rudder, a fluid motor for moving said rudder, a reversible pump for actuating the motor to shift the rudder, a control shaft adapted to be manually controlled, 20 a tubular follow-up shaft surrounding said control shaft, a tubular differential shaft surrounding said control shaft, front and rear differential gear wheels connected, respectively, with said differential shaft and said follow-up shaft, a floating differential gear pinion meshing on its opposite sides with opposing parts of said gear wheels, 25 a spider turning about the axis of said control and follow-up shafts and having an inner section arranged between said gear wheels and carrying 30 said floating differential gear pinion and an outer section which turns on said differential shaft, a trip device connected with the front section of said spider and having a trip arm provided with a tappet and a hub having a receding clearance 35 face and a cylindrical locking face extending circumferentially around the hub from one side of said clearance face to the other side thereof, a lock arm having a radial slot adapted to receive said tappet and curved locking faces on opposite sides of said slot adapted to engage said circumferential locking face, a rock shaft carrying 40 said lock arm, an operating arm connected with said rock shaft and operatively connected with said pump for controlling the same, a restoring gear pinion connected with said tubular follow-up shaft, and a restoring gear rack meshing with 45 said restoring gear pinion and operatively connected with said rudder and motor to move therewith.

FRED GASCHE.
